(Cl. D80—11)

To all whom it may concern:

Be it known that I, Martin M. Drogin, a citizen of the United States, residing in Philadelphia, county of Philadelphia, Commonwealth of Pennsylvania, have invented a new, original, and ornamental Design for Display Cabinet, of which the following is a specification, reference being had to the accompanying drawings, forming a part thereof.

Fig. 1 is a perspective view of the display cabinet, showing my design; and

Fig. 2 is a top plan view thereof.

I claim:

The ornamental design for a display cabinet, as shown.

MARTIN M. DROGIN.
